US0D1041599S

(12) **United States Design Patent** (10) Patent No.: **US D1,041,599 S**
(45) Date of Patent: ** Sep. 10, 2024

(54) **APPARATUS FOR DEVELOPING MUSCLES**

(71) Applicant: **Umutcan Bilir**, Ankara (TR)

(72) Inventor: **Umutcan Bilir**, Ankara (TR)

(**) Term: **15 Years**

(21) Appl. No.: **35/517,899**

(22) Filed: **Jun. 8, 2023**

(80) **Hague Agreement Data**

Int. Filing Date: **Jun. 8, 2023**

Int. Reg. No.: **DM/230336**

Int. Reg. Date: **Jun. 8, 2023**

Int. Reg. Pub. Date: **Jul. 28, 2023**

(51) **LOC (14) Cl. 21-02**

(52) **U.S. Cl.**

USPC **D21/691**

(58) **Field of Classification Search**
